UNITED STATES PATENT OFFICE.

JOSEPH HEAPS, OF METHUEN, MASSACHUSETTS, ASSIGNOR TO GEORGE M. ARRAGG,
OF LAWRENCE, MASSACHUSETTS.

LIFTER MOTION FOR CAP-SPINNING FRAMES.

Application filed April 1, 1922. Serial No. 548,729.

To all whom it may concern:

Be it known that I, JOSEPH HEAPS, a citizen of the United States, residing at Methuen, in the county of Essex and State 5 of Massachusetts, have invented certain new and useful Improvements in Lifter Motions for Cap-Spinning Frames, of which the following is a specification.

This invention relates to builder motions 10 for worsted spinning frames.

Specifically, it is an improvement on what 15 is known as the Scaife motion extensively used on worsted cap spinning frames for the purpose of building the yarn in a certain way on a bobbin.

The yarn is built by starting a small cone 20 near the butt and increasing the size up to a certain limit, then building similar cones of yarn one on top of the other until the bobbin is filled.

In the drawings, Figure 1 is a front elevation of part of a cap spinning frame showing my device in position, some parts being broken away for clearness.

Fig. 2 is a sectional elevation from the 25 right of line 2—2 of Fig. 1.

Fig. 3 is a front elevation of my devices in position.

Fig. 4 is an elevation of Fig. 3 from the 30 right.

Fig. 5 is a rear elevation partly in section of a modified form of my device.

In the drawings, A represents the frame 35 of a cap spinning machine having a stationary spindle rail B which supports spindles 10 carrying caps 9, and C is a bobbin rail carrying bobbins 11 which is raised and lowered by lifter mechanism of a well known type controlled by the Scaife motion.

This lifter mechanism includes vertical 40 rods 12 which carry rail C, and are moved up and down by means of chains, such as 13, which run over pulleys 14 and 15 and are attached to a chain bar, such as 16, 45 which has a vertical upturned end at 17 which bears against the end of motion screw F.

This motion screw F is threaded at 20 and 50 passes through a motion nut 22 carried near its top by a long lever E which is pivoted at 25 to any suitable part of the frame of the machine.

This motion screw extends out through a sleeve 30 carried in bearings 23 fixed to the

frame A of the machine, and generally has 55 a collar 32 outside the bearing 23, a wind-up gear K and hand wheel P. There is a suitable spline, fixed inside sleeve 30 which rests in a suitable groove in the plain end of screw F whereby sleeve 30, collar 32, gear 60 K and hand wheel P are slidable on said plain end and are revoluble therewith. The driving gear H normally engages wind-up gear K but when it is desired, after the frame is doffed, to start it again and therefore to raise rail C, the latch 100 is lifted from groove 2 and the wheel P, with the other parts K and 32 carried by sleeve 30, is pulled out by hand to free gear K from gear H, after which the motion screw F is 65 revolved and thus rail C lifted to the desired position. K and H are reengaged and the parts locked by latch 1, all in a well known manner.

Long lever E is pivoted and along it in 70 guide 21 is slidable what is known as a monkey or roll stand O having a roller 26 which engages the surface 52 of what is known as the short lever N pivoted to the frame at 50 and having a roller or cam follower 51 in engagement with the builder cam M. This builder cam M imparts the up and down traverse motion, and the face 52 of short lever N may be adjusted as shown in the dotted lines in Fig. 1 so that 75 while the monkey O is moving up from the dotted to the full line position, it tends to allow the motion nut 22 at the top of long lever E to move to the right, thus counter-acting to some extent the screwing action 80 of motion screw F. Below monkey O on the long lever E are adjusting nuts 40 on screw 39 which limit the traverse motion of monkey O.

The above described parts are all old and 85 well known.

My preferred construction is shown in Figs. 1 to 4. On the threads 20 of motion screw F, I locate a threaded barrel 56 and from this extends the chain 57 to monkey 100 O whereby when the shoulder 55 comes in contact with barrel 56, it revolves the winding-up chain 57 and lifts monkey O. I provide also the returning spring 58, the tendency of which is to pull down monkey 105 O and to keep chain 57 tight.

The barrel 56 is a revoluble member threaded loose on threads 20 and revoluble

therewith only when engaged by the shoulder 55, and the chain 57 is a connecting member which at all times extends between the monkey O and said member 56 and which moves therewith when member 56 revolves.

The difference between the new construction, and the old construction is that in the old construction a gear engages and disengages a rack, while in the new construction the members which perform the same functions are in continual engagement thereby preventing wear and banging.

As shown in Fig. 5, I may use in connection with a rack L, a gear, such as 84, which is always in engagement therewith and which has teeth 85 which are engaged at the appropriate time by teeth 86 on shoulder 87 of screw F when it is screwed up.

Gear 84 is not threaded but is loose on the threads 20, and the returning spring 88 between 84 and 22 and stop 89 fixed to rail B keep gear 84 and rack L always in engagement. They limit the movement of the parts and return them to their normal positions.

In this construction, the rack is the connecting member which always extends between monkey O and the revolute member 84 loose on the threads of the motion screw and normally revolute thereon but revolute therewith when engaged by teeth 86 on shoulder 87.

I claim:

1. In a Scaife builder motion for spinning frames; the combination with a motion screw having a shoulder beyond which its threads extend; of a long lever; a motion nut through which the motion screw threads pass, carried by the free end of said long lever; a monkey slideable on said long lever; a revolute member loose on the threads of said motion screw and revolute therewith, only when engaged by the shoulder; and a connecting member which at all times extends between said monkey and said revolute member and which moves the monkey when the revolute member revolves.

2. In a Scaife builder motion for spinning frames; the combination with a motion screw having a shoulder beyond which its threads extend; of a long lever; a motion nut through which the motion screw threads pass, carried by the free end of said long lever; a monkey slideable on said long lever; a revolute member loose on the threads of said motion screw and revolute therewith, only when engaged by the shoulder; a flexible connecting member which at all times extends between said monkey and said revolute member and which moves the monkey when the revolute member revolves; and a monkey returning spring between the monkey and the long lever.

JOSEPH HEAPS.
